UNITED STATES PATENT OFFICE.

HARRY D. MOSAUER, OF NEW YORK, N. Y., AND LEON LAUB, OF NEWARK, NEW JERSEY.

DICE.

Application filed October 15, 1921. Serial No. 507,972.

To all whom it may concern:

Be it known that we, HARRY D. MOSAUER and LEON LAUB, citizens of the United States, residing at New York, in the city, 5 county, and State of New York, and Newark, in the county of Essex and State of New Jersey, respectively, have invented certain new and useful Improvements in Dice; and we do hereby declare the following to 10 be a full, clear, and exact description of the invention, such as will enable others skilled in the art to which it appertains to make and use the same.

The objects of this invention are to provide 15 a pair of dice which may be handled and played as a unit; to provide in such a unity means for obtaining the usual combination of numbers which may be obtained by use of two separate dice; to provide an 20 article which will always rest with the dice face exposed upwardly; to make the dice roll straight when cast or thrown; to secure simplicity of construction, ease of manipulation and neatness of appearance, and to obtain 25 other advantages and results as may be brought out in the following description.

Referring to the accompanying drawing, in which like numbers of reference indicate similar parts throughout the several views; 30 Figure 1 is a side elevation of the dice embodied in our invention;

Figure 2 is a longitudinal central section through the same, and

Figure 3 is an end view of the dice.

In the specific embodiment of the invention illustrated in said drawing, the reference numerals 1, 1 indicate disc like rotary members the edge or circumference of which is shown as flattened off as a hexagon. These 40 rotary members are arranged so as to stand up upon edge and expose one of the flattened faces upwardly. These flattened faces may have any suitable markings upon them such as the usual dots 2 ordinarily used upon dice. By providing six of these faces, the dots will number one to six on the several faces as is usual in dice. Each of the rotary members 1 has a central hole 3 through which any suitable pivot or trunnion 4 may 45 be inserted for the said member to rotate upon. This pivot 4 is shown in the present instance as comprising pins inserted toward each other in the two rotary members and having their ends secure in a connector 50 55. The pins have heads at their outer ends

for preventing the rotary members from sliding off and the connector 5 is large enough to prevent the rotary members from moving toward each other. The complete device therefore resembles in some respects 60 a dumb-bell, and as the rotary members are separated far enough in proportion to their diameter, the device when cast or thrown will come to rest with both rotary members upon the surface in an upright position. 65 Consequently they will both show some number on the top just as a pair of individual dice when cast will show numbers. By virtue of the rotatable mounting of both of the members which are upon the pivot 4, 70 any combination of numbers from one to six may be obtained, and furthermore the dice when cast will have a tendency to roll along straight since the same is balanced and both members are freely rotatable. 75

Obviously other means of mounting the rotary members may be employed, the essential feature being that both of the members are rotatable and prevented from coming together or coming off. Furthermore, 80 the rotary members may have more or less than six flattened surfaces in accordance with the desires of the manufacturer, and other detail changes and modifications may be made in the construction and use of our 85 improved dice without departing from the spirit or scope of the invention, and we do not wish to be understood as limiting ourselves except as set forth in the following 90 claim when construed in the light of the prior art.

Having thus described our invention, we claim:

In a device of the character described, the combination of a pair of independently rotatable dice members having relatively short axes compared to their diameters, a connector having ends adjacent the said dice members, said ends having relatively short diameters compared to the diameters of said dice members, whereby said dice members may rotate freely with minimum friction, and means on said connector rotatably supporting said dice members through said axes. 95 100 105

In testimony whereof we affix our signatures.

HARRY D. MOSAUER.
LEON LAUB.
